UNITED STATES PATENT OFFICE.

ALFRED F. MEYER, OF ROANOKE, ILLINOIS.

PORTABLE ELEVATOR.

No. 898,637.

Specification of Letters Patent.

Patented July 21, 1908.

Application filed November 15, 1907. Serial No. 402,349.

To all whom it may concern:

Be it known that I, ALFRED F. MEYER, citizen of the United States, residing at Roanoke, in the county of Woodford and State of Illinois, have invented certain new and useful Improvements in Portable Elevators; and I do hereby declare that the following is a full, clear, and exact description of the invention, which will enable others skilled in the art to which it appertains to make and use the same.

This invention relates to portable elevators of that class used in conjunction with wagon dumps.

The object of the invention is to provide an elevator of peculiar arrangement well adapted for handling ear corn, shelled corn and the small grains.

An object also is to provide a simple form of elevator preferably occupying a vertical position and provided with peculiar means in its boot for permitting the elevating buckets to readily enter said boot though the latter may be full of grain, even in the form of corn in the ear.

A further object is to provide for the boot of an elevator a shield behind and beneath which the empty buckets may pass into the said boot for gathering their loads.

Another object is to provide in an elevator peculiar dumping means at its top for automatically emptying its loaded buckets.

In the accompanying drawings Figure 1 is a vertical section of my elevator showing a conveyer or drag in connection therewith in cross section and also showing a part of a wagon-platform. Fig. 1^a is a top view of a vertically adjustable idler. Fig. 1^b is a top view of a block for carrying the idler. Fig. 2 is a horizontal section of the elevator, showing the conveyer together with a part of the platform. Fig. 3 is an elevation of the platform showing the elevator and conveyer. Fig. 4 is a top view of the elevator limbs showing a series of sprocket wheels.

A indicates a platform for the wagon to be unloaded and to which is attached at one side, in any suitable manner, an elevator boot B which carries the members or limbs C and D of the elevator. In the elevator boot at E is a shaft provided with sprocket wheels the positions of which are indicated in broken lines in Figs. 1 and 3 at F. These said wheels carry the elevator chains indicated at G which are provided at intervals

with buckets H. The said sprocket wheels F are of such a diameter as to centralize the chains within the portions or legs C and D in the elevator so that the buckets can properly travel therethrough. In the elevator boot and forming the bottom therefor is a semi-cylindrical member J, preferably of sheet metal, arranged concentrically with the perimeters of the sprockets and placed such a distance therefrom that the sides of the buckets G will drag thereupon so as to gather the grain properly. Concentric with the member or bottom J is a shield or guard K also of sheet metal beneath which the buckets H travel as they enter the boot, the elevator member C being properly extended to meet said guard so that a closed passage extends down into the bottom of the boot. The upper ends of the portions or legs C and D of the elevator support two arched plates L in suitable manner and each plate carries two sets of sprockets M N there being two of the former above the leg D and two of the latter above the limb C, Fig. 4. It will be noted that there are two sprocket chains 80 both of which are shown in Figs. 2 and 3, and consequently there must be corresponding pairs of the wheels.

The buckets H are carried and suspended between the chains and consequently they 85 pass between the wheels M and N. Between the wheels M and N are idlers O and these idlers are so positioned that as the chain passes from the upper periphery of the wheel M to said idler the bucket is tipped as 90 shown in Fig. 1 so as to deliver its contents into a chute P held in any suitable manner between the elevator limbs C and D. The buckets on being emptied pass the wheels N and down into the elevator. The idlers O 95 are preferably vertically adjustable so that the tension of the chains may be varied.

Extending across the platform A is the conveyer or drag Q usually employed on wagon dumps and which is provided with 100 shafts R for carrying the usual interior sprockets one of which is indicated at S in broken lines in Fig. 3. The shaft R nearest the elevator forms a pivot for the conveyer and is held in suitable bearings T attached to 105 said elevator. This conveyer extends between the legs of the elevator and discharges the grain into the boot between said legs. This arrangement admits of making the boot substantially longer in horizontal 110

measurement than the total width of the elevator itself. Furthermore, it admits of raising the conveyer and folding it and the elevator in compact form for shipping or storing purposes. In addition to this the chute P being short and having a position between the legs C and D above and in the same vertical plane with the conveyer occupies but little space when the device is put in shape 10 for transportation.

Journaled upon the platform in bearings U is a shaft V extending at right angles to and beneath the conveyer. This shaft is provided with a beveled gear wheel W meshing 15 with and driving a similar beveled gear X on the shaft E of the elevator, both wheels being shown in broken lines in Fig. 2. On said shaft V is a sprocket wheel 2 for driving a sprocket wheel 3 on one of the shafts R of 20 the conveyer by means of a sprocket chain. Motion imparted in the proper direction to the shaft V will drive the elevator chain in the proper direction while at the same time motion is imparted to the chain of the conveyer so that grain dumped into the latter will be discharged into the elevator boot. In falling into the boot the shield prevents the grain obstructing the path of the buckets where they enter the elevator boot so that 30 said buckets can pass downward into the boot between said shield K and the bottom J and as they emerge from beneath said shield the grain is scooped up. The conveyer Q by being pivoted on the elevator can 35 be readily tilted on end out of the way to permit the loaded wagon to pass upon the platform in position for delivering its load into said conveyer.

I am not confined, of course, to using the 40 platform A, I merely having shown this because it is used in many forms of wagon dumps. It is only necessary to provide such a support as will properly hold the elevator in position for doing its work and the wagon 45 could remain upon the ground in position for discharge. I may make various changes in the elevator as will come within the meaning of the invention.

Having thus described my invention, I 50 claim:

1. An elevator, devices therein for elevating grain, and means in the boot of the elevator adjacent to and above the path of travel of the elevating devices for keeping a portion of such path free of grain to permit free entrance of the elevating devices into said boot.

2. In an elevator, devices therein for elevating grain, and means extending into and 60 fixed in position within the boot of the elevator adjacent to the path of travel of the elevating devices and terminating substantially at the lowest point of travel of said devices and behind which the latter are adapted to 65 travel for the purposes set forth.

3. In an elevator and means lying within the boot of the elevator adjacent to the path of travel of the elevating devices for covering the latter for a portion of their travel within said boot for the purposes set forth. 70

4. In an elevator having a leg and boot, grain elevating devices adapted to travel downward into and through said leg and boot, and means forming a continuation of one side of the leg and extending downward 75 into the boot adjacent to and above the path of travel of the devices to cover them during a portion of their travel through said boot, for the purposes described.

5. An elevator boot, grain elevating devices adapted for traveling downward into and through the same, and means extending downward into and through a portion of the boot above the path of travel of the said elevating devices for keeping a portion of said 80 path free of grain for the purposes set forth. 85

6. The boot and legs of an elevator, means to travel through said legs and boot; grain elevating devices carried thereon, and means forming a continuation of one of the legs and 90 extending downward into the boot adjacent to and above and covering the path of movement of the elevating devices and beneath which the latter travels and from which they emerge to gather their loads in the upward 95 movement.

7. An elevator boot, grain elevating devices, and means positioned vertically in the upper part of the boot and extending downward into the latter concentric with and above the path of travel of the elevating devices to substantially the lowest point of travel of said devices for the purposes set forth. 100

8. In an elevator, elevating devices, a 105 curved bottom concentric with the curve of travel of the elevating devices, a guard substantially concentric with the bottom and partially covering said bottom and providing a space between it and the bottom to hold the grain away from the latter and provide a 110 free passage for the elevating devices for the purpose set forth.

9. In an elevator, elevating devices, a 115 curved bottom concentric with the curve of travel of the elevating devices, a guard concentric with and separated from the bottom and extending substantially to a point above the lowest point of said bottom for providing a free space through which the elevating 120 devices may travel for the purposes set forth and described.

10. An elevator comprising a boot, legs opening thereinto, grain elevating devices adapted for traveling downward through one 125 leg and upward through the other, and means extending from the lower end of the first said leg downward into the boot above the path of travel of the elevating devices to constitute a passage in said boot substantially free 130

of grain to substantially the lowest point of travel of said devices for the purposes described.

11. An elevator comprising a boot, legs opening thereinto, grain elevating devices adapted for traveling downward through one leg and upward through the other, and means extending from the lower end of the first said leg downward into the boot above the path of travel of the elevating devices to constitute a passage in said boot substantially free of grain to substantially the lowest point of travel of said devices, the bottom of the boot and said means lying concentric with the said path of travel substantially as and for the purposes set forth.

12. In an elevator, elevating devices therefor, a curved bottom for the elevator arranged concentrically to the curve of travel of the said elevating devices, a guard concentric with and spaced apart from said bottom and forming an inclosing space for the descending elevating devices, and means at the top of the elevator for inverting the elevating members for causing them to successively discharge their loads substantially in the manner set forth.

13. An elevator having legs open at the top, grain elevating devices to travel in said legs, means for carrying said devices, wheels at the top of each leg for carrying and guiding said means out of one leg and into the other, and adjustable idlers stationed between said wheels and adapted by their position with reference to said wheels to cause the same to be tilted to deliver their contents.

14. An elevator comprising a boot, a member for carrying ascending and descending elevating devices, means for carrying and driving said member, said boot having an open top for the reception of grain between the stretches of said member.

15. An elevator having two legs and a boot, the latter being open at its top between the legs, and a conveyer arranged to discharge its contents into said boot between the legs.

16. An elevator having two legs and a

boot, the latter being open at its top between the legs, and a conveyer carried by the elevator and arranged to discharge its contents 50 into said boot.

17. An elevator having two legs and a boot, the latter being open at its top between the legs, and a conveyer pivotally carried by the elevator into a position to discharge grain 55 into said boot, and adapted to occupy a position on and between and substantially parallel to them.

18. An elevator having two legs and a boot, the latter being open at its top between 60 the legs, a conveyer pivoted to and carried by the elevator in a position to discharge grain into said boot and adapted to be raised on its pivot and occupy a position on end parallel to the said elevator, and means permanently 65 carried by the conveyer and elevator for the transmission of power from one to the other.

19. In a portable device of the class described, a platform, an elevator comprising two legs and a boot mounted thereon, said 70 boot being open at its top between the legs, a conveyer carried by the elevator in position to discharge grain into the boot and adapted to tilt on end between the legs, and means on the conveyer and elevator through which 75 one is driven from the other.

20. In a device of the class described, an elevator comprising a boot open at its top and having two elevator-legs mounted thereon and opening thereinto, a conveyer pivotally carried on said legs and adapted to discharge into said boot and adapted also to tilt on end between said legs, means within the elevator for elevating grain, and a chute at the top of and between the legs and in the same vertical plane with the conveyer to receive grain from the grain elevating means substantially as shown.

In testimony whereof I affix my signature, in presence of two witnesses.

ALFRED F. MEYER.
